UNITED STATES PATENT OFFICE

2,575,768

SKIMMER

Harold C. Pearsall, Houston, Tex.

Application May 27, 1949, Serial No. 95,756

5 Claims. (Cl. 210—51)

1

The present invention relates to new and useful improvements in skimmers for easily and quickly skimming grease from the surface of soup and other liquid foods.

An important object of the invention is to provide a two-part grease collecting chamber in which grease is collected by forcing the lower-most part downwardly in a vessel containing the liquid and constructing the bottom of said lower part in the form of an inverted funnel through which the grease is forced into the chamber in a fountain action.

A further object of the invention is to provide means for locking the parts of the chamber to each other for convenient removal for cleaning purposes.

A still further object is to provide a two-part grease collecting chamber into which grease enters through the lower part and providing the upper part with a pouring spout constructed to pour the grease from the chamber by inverting the position thereof after removal from the vessel from which the grease is collected.

Another object is to provide a drip collecting trough or channel at the connected edges of the two parts of the chamber and in which grease dripping from the lower edges of the device is collected during the inverting action.

A still further object is to provide a central window opening for the chamber by means of which the grease collecting or skimming action may be observed to avoid waste in removing part of the liquid food with the grease.

A still further object is to provide a novel handle construction for inverting the skimmer chamber into its pouring position.

A still further object is to provide a device of this character of simple and practical construction, which is neat and attractive in appearance, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the two-part chamber in skimming position.

Figure 2 is a similar view showing the device inverted in pouring position.

Figure 3 is an enlarged vertical sectional view taken on a line 3—3 of Figure 1.

2

Figure 4 is an enlarged longitudinal sectional view of the handle.

Figure 5 is a transverse sectional view taken on a line 5—5 of Figure 4.

Figure 6 is an enlarged fragmentary group perspective view of the locking lug connecting the two parts of the chamber to each other, and

Figure 7 is an enlarged fragmentary perspective view of the pouring spout.

Referring now to the drawings in detail wherein for the purpose of illustration I have disclosed a preferred embodiment of the invention, the numeral 5 designates generally the two-part grease collecting chamber comprising a lower grease collecting part or section 6 and an upper pouring part or section 7 forming a grease collecting chamber.

The parts 6 and 7 are of annular construction and the bottom 8 of lower part 6 is of inverted funnel or conical shape with an upstanding tube 9 at its center. The lower edge of bottom 8 is suitably secured within lower section 6 above the lower edge thereof to provide a flange 10 projecting downwardly below the bottom.

The side wall of upper section 7 is formed with an annular shoulder 11 which rests on the upper edge of lower section 6 with a gasket 12 therebetween and the lower edge of upper section 7 telescopes over the upper edge of lower section 6 and is spaced outwardly therefrom to form an annular drip trough or channel 13.

Locking lugs 14 are suitably secured in channel 13 and locking lugs 15 are suitably secured to the outer upper portion of lower section 6 and are formed with sloping confronting edges for locking engagement with each other by a partial rotary movement of one section relative to the other.

An inverted pouring spout 16 is formed outwardly at one side of upper section 7 with openings 17 in the side wall of the upper section leading to the spout. The shoulder 11 is also formed with a drain opening 18 in the drain channel 13 also leading to the spout.

The top 19 of upper section 7 is of frusto-conical construction sloping toward its center and formed at its central portion with a window opening 20 in which a transparent disk or window 21 is removably positioned.

A handle includes a rod or core 22 having an angular inner end 23 suitably secured in an upstanding position to the outer surface of upper section 7 and with the free end 24 of rod or core 22 projecting substantially horizontally outwardly therefrom. An outer hand grip 25 of square

shape in cross section is suitably fixed to the outer end 24 of rod or core 22 and an inner hand grip 26 is rotatably mounted on rod or core 22 inwardly of hand grip 25.

In the operation of the device, the top and bottom chamber sections 6 and 7 are locked together by the lugs 14 and 15 and the assembled sections, with bottom section 6 lowermost, are placed in a cooking vessel 27 to force the section 6 downwardly into the liquid in the vessel. Grease carried on the surface of the liquid will be forced upwardly through tube 9 in a fountain action to enter the chamber formed of sections 6 and 7 and is collected therein. The action of the grease entering the chamber is observed through window 21 and when the grease has been sufficiently removed from the liquid in vessel 27 the device is removed from the vessel and hand grip 25 turned while hand grip 26 is held stationary to invert the device. The grease may then be poured from spout 16.

Any grease dripping from the edge of the device as it is inverted will be caught in drip channel 13 and conveyed to the spout.

Having described the invention, what is claimed as new is:

1. A grease skimmer comprising a two-part chamber adapted for placing in a covering position on a cooking vessel and including a top section and a bottom section, means locking the sections to each other, an inverted funnel shaped bottom in the bottom section into which grease on the surface of liquid in the cooking vessel enters by a fountain action when the chamber is forced downwardly into the liquid, and a pouring spout for the top section.

2. A grease skimmer comprising a two-part chamber adapted for placing in a covering position on a cooking vessel and including a top section and a bottom section, means locking the sections to each other, an inverted funnel shaped bottom in the bottom section into which grease on the surface of liquid in the cooking vessel enters by a fountain action when the chamber is forced downwardly into the liquid, and an inverted spout for the top section turned into a pouring position by an inverting movement of the chamber.

3. A grease skimmer comprising a two-part chamber adapted for placing in a covering position on a cooking vessel and including a top section and a bottom section, means locking the sections to each other, an inverted funnel shaped bottom in the bottom section into which grease on the surface of liquid in the cooking vessel

enters by a fountain action when the chamber is forced downwardly into the liquid, a window in the top of the chamber to observe the fountain action, and a pouring spout for the top section.

5. A grease skimmer comprising a two-part chamber adapted for placing in a covering position on a cooking vessel and including a top section and a bottom section, means locking the sections to each other, an inverted funnel shaped bottom in the bottom section into which grease on the surface of liquid in the cooking vessel enters by a fountain action when the chamber is forced downwardly into the liquid, an inverted pouring spout for the top section turned into a pouring position by an inverting movement of the chamber, and an external inverted drip channel on the top section having a drain opening leading to the spout.

6. A grease skimmer comprising a two-part chamber adapted for placing in a covering position on a cooking vessel and including a top section and a bottom section, means locking the sections to each other, an inverted funnel shaped bottom in the bottom section into which grease on the surface of liquid in the cooking vessel enters by a fountain action when the chamber is forced downwardly into the liquid, an inverted pouring spout for the top section turned into a pouring position by an inverting movement of the chamber, and a handle for the chamber and comprising a fixed hand grip, and a rotatable hand grip, one hand grip holding the chamber in an elevated position while the other hand grip inverts the chamber.

HAROLD C. PEARSALL.
